JOB G. LUSCOMB, OF TAUNTON, MASSACHUSETTS.

Letters Patent No. 91,032, dated June 8, 1869.

IMPROVEMENT IN FLY-FRAME.

The Schedule referred to in these Letters Patent and making part of the same.

To all whom it may concern:

Be it known that I, JOB G. LUSCOMB, of Taunton, in the county of Bristol, and State of Massachusetts, have invented a new and useful Improvement in Fly-Frames for roving-machines; and I do hereby declare that the following is a full, clear, and exact description thereof, which will enable others skilled in the art to make and use the same, reference being had to the accompanying drawings, forming part of this specification, in which—

Figure 1, Sheet I, represents a front elevation of my improved fly-frame.

Figure 2, Sheet II, is a vertical transverse section of the same, taken on the plane of the line xz , fig. 1.

Figure 3, Sheet II, is a detail horizontal section, on an enlarged scale, of the same, taken on the plane of the line yy , fig. 2.

Figure 4, Sheet II, is a detail vertical section of the same, taken on the plane of the line zz , fig. 3.

Similar letters of reference indicate corresponding parts.

This invention has for its object the production of a new apparatus for adjusting the belt on the cones of a fly-frame, for regulating the velocity of the bobbins.

The invention consists in a novel arrangement of devices for connecting the rack, by which the belt is adjusted, with the contact-shaft, and with a clutch-gear, whereby certainty of action, and a suitable degree of decrease of motion are obtained.

All the racks heretofore used on fly-frames were connected with very complicated apparatus, and their operation was ineffective.

The action of my apparatus is positive. It can be used with cones of suitable length, and its degree of motion can be changed with very great facility.

A, in the drawing, represents the frame-work of my improved apparatus.

B is the sliding rack, supported in a horizontal position on the frame A, and connected in suitable manner with the belt C of the cones D E, as indicated in fig. 1.

F is the contact-shaft, which is, by a segmental pinion, a, geared with the upper cone, D, and its action is controlled by means of a spring, and by two arms, b b, as usual. It thereby receives intermittent rotary motion, and transfers the same, by suitable gearing, c, to a horizontal shaft, G, which has its bearings in arms attached to the frame A, as is clearly shown in fig. 1.

The shaft G is, by means of a bevel-pinion, d, connected with a bevel-wheel, e, which is fitted upon a vertical arbor, f, that projects from an arm, g, of the frame A.

On the arbor f is also mounted a pinion, h, which meshes into a toothed wheel, i, that revolves loosely on a pin, j, that projects from the arm g.

The pin j is fitted through a curved slot in the arm g, which slot is part of a circle described around the arbor f, and the pin j can therefore be adjusted in the slot, and still be always equidistant from f.

On the pin j is fitted another toothed wheel, k, which is, by means of a pin, l, or by other suitable means, connected with the wheel i, so as to turn with it.

The wheel k meshes into a toothed wheel, m, that turns loosely on the rack-shaft H. Thus the motion of the contact-shaft is transmitted to the said wheel m on the rack-shaft.

The velocity of the wheel m is regulated by adjusting the pin j in the slot, so as to allow a larger or smaller wheel to be used for the wheel k. Thereby the motion of the rack can be varied at pleasure, without varying that of the contact-shaft.

On the rack-shaft H is arranged a sliding clutch, I, which, when let down upon the wheel m, as in fig. 1, will connect the same with the shaft H, so that the latter will also be turned.

On the shaft H is mounted a toothed wheel, n, which meshes into the rack B, so that thus the motion of the contact-shaft is transmitted to the rack.

The clutch I is, by means of a fork, o, connected with a bell-crank, J, that is pivoted to the frame A, as shown in fig. 1.

This bell-crank is, by means of an arm, K, connected with a lever, L, that is pivoted to the upper part of the frame A.

An arm projects from the lever L, to carry a weight, M, that has the tendency to swing the lever so as to raise the clutch off the wheel m.

N is a notched bar, pivoted to the end of the lever L, and secured in position by means of a notch or shoulder thereon, catching over a fixed plate, p, as indicated by dotted lines in fig. 1.

In fig. 1 the parts are represented as ready to work. The belt C is on the thin end of the convex pulley, the clutch is in gear, and the rack as far out as possible.

As the operation proceeds, the rack will be gradually moved in the direction of the arrow shown in fig. 1, and will thereby gradually move the belt C toward the thicker end of the cone E, to make the bobbins turn slower.

A pin, r, projects from the rack, and works under the bar N, as in fig. 1.

When the belt C is on the thick end of the cone E, the pin r strikes a rounded shoulder formed on the bar N, and raises the said bar off the plate p. Thereby the weight M is free to act on the lever L, which is swung so as to push the rod K, and to swing the crank J, and consequently raise the clutch off the toothed wheel m. The rack is thus instantly thrown out of gear as soon as the bobbins are full.

The lever L may have an upper arm, s, which is connected with the shipper-bar O, so that when the

bar N is thrown off the plate p, the main belt may also be thrown upon the loose pulley.

When the rack-bar is thus out of gear, the rack-shaft H will also be free, and can be turned by hand, to draw the rack back again into its original position, and for this purpose, a crank or hand-wheel, t, is mounted on the shaft H.

When the machine is to be restarted, to fill a new set of bobbins, the bar N must be pushed in and locked to the plate p, in order to have the clutch thrown into gear.

Having thus described my invention,
I claim as new, and desire to secure by Letters Patent—

1. The combination of the horizontal shaft G and

gear-wheels d, e, h, i, and k, for connecting the shafts F and H, the wheel K being removable, to change the motion, as specified.

2. The combination of the weighted lever L, the clutch-gear I, and the retaining-bar N, when connected together, substantially as herein shown and described, and operating as specified.

3. The rack-bar B, provided with a pin, r, for the purpose of automatically raising the bar N and clutch I, as set forth.

JOB G. LUSCOMB.
